UNITED STATES PATENT OFFICE.

MEADE L. ZIMMER, OF CORDOBA, ARGENTINA.

INTERNAL-COMBUSTION ENGINE.

Application filed November 3, 1923. Serial No. 672,453.

To all whom it may concern:

Be it known that I, MEADE L. ZIMMER, a citizen of the United States, residing at Cordoba, Argentina, have invented a new and useful Internal-Combustion Engine, of which the following is a specification.

Although particularly adapted for an internal combustion engine, this invention is capable of general use. At any rate it is to 10 be used always in connection with an engine having a plurality of cylinders and pistons in which the pistons operate alternately.

The principal objects of the invention are to provide an engine, particularly an internal combustion engine, with reciprocating pistons that rotate uniformly in the cylinder so that the piston at no time need actually touch the walls of the cylinder, and the piston rings will act as laps to tend to make 20 the fit between the rings and walls of the cylinders more and more perfect as the engine continues to be used, thereby giving increased power; to provide for the elimination of all clogging of the spark 25 plugs, and the formation of carbon by the above mentioned arrangement as no oil will be able to get by the piston rings; and to provide a uniform rotation imparted at its maximum efficiency at all times throughout 30 the stroke, thus eliminating vibration, as well as giving great power and smoothness. It also somewhat reduces the cost of an internal combustion engine to eliminate the crank shaft and crank motion as well as the 35 piston slaps or pounding of the connecting rods, thus securing silent operation. With this arrangement I secure increased compression, eliminate carbon formation, eliminate dirty spark plugs, reduce fuel consumption, 40 increase the utilization of the energy expended, secure greater power applied more uniformly, and provide all this with a reduction in vibration.

Other objects and advantages of the invention will appear hereinafter.

Reference is to be had to the accompanying drawings, in which

Fig. 1 is a central longitudinal sectional view of a four-cylinder internal combustion 50 engine constructed in accordance with this invention;

Fig. 2 is a transverse central sectional view of one of the elements thereof;

Fig. 3 is a view similar to Fig. 1 showing 55 a modification; and

Fig. 4 is a view of the same similar to Fig. 2.

In the preferred form shown in Figs. 1 and 2, the invention is shown as applied to an internal combustion engine of well known 60 type having four cylinders 10, although it can be applied to an engine with any other number of cylinders.

In each cylinder there is a piston 11 provided with packing rings as usual and having a piston rod 12 extending through a gland 13 in the end of the cylinder. Each of these piston rods is provided with a radial stud 14, on the end of which is a roll 15. This roll is located in a track 16. This track is spaced at an equal distance all around from the axis of the cylinder and from the rod. It is provided with a cam-groove fitting the roll 15 and extending along the rod lengthwise and entirely around it so that it forms a helical elliptical path for the roll. The curve of this endless track is designed in such a way as to cause the longitudinal motion of the rod 12 to rotate the rod through a half circle on one stroke and the other half circle on the back stroke, bringing the roll back in a complete stroke forward and back to its original position and keeping the rotation of the rod constant.

It will be seen, therefore, that the end of the rod can be provided with a gear 17, as for example, a bevel gear, meshing with another gear on a shaft 19 and that the power can be transmitted from the piston to the shaft as a rotation. In other words, the reciprocation is converted into a rotation and that rotation is made constant and continuous.

The above description applies to one of the piston and cylinder elements of the engine and no means is described in connection with it for bringing the piston back to original position and rotating the same through a second half of the revolution. This is accomplished in a multi-cylinder engine by arranging the pistons to operate at different times, that is, alternately, and placing a gear, preferably a spiral gear 20, on each piston rod and slidingly keyed thereto, which will rotate with the rod but will not reciprocate. This gear is mounted between face bearings 21 for that purpose. These several gears 20 on the several piston rods mesh directly together so that at those times 100 105 110

when there is no power to move one rod longitudinally another one will act to operate it.

The operation will be obvious from what has been said. Starting with the first cylinder at the moment of explosion, the piston descends and in so doing is given a rotary motion through a half circle. This of course rotates all the pistons through the same angle. By the time the first piston has reached the end of its stroke the charge in #2 cylinder explodes, giving a second impulse to the motor which raises the first piston, pushing out the burnt gas. When it has again reached the end of its stroke, explosion takes place in #3 cylinder and #1 piston is forced to descend, drawing in a new charge. The charge now explodes in #4 which causes the first piston to rise, thus compressing the charge and bringing it back to original position ready to explode a new charge and start the cycle over again. I have not shown the sparking arrangement, as any ordinary means can be used. It will be understood that each piston rod slides back and forth through the gear 20 at the bottom.

With this construction the several pistons will rotate uniformly in their cylinders and do not need to actually touch the walls thereof. The piston rings act as a lap to tend to make the fit between the rings and walls more and more perfect after wear. As no oil is able to get by the piston rings the formation of carbon is eliminated, together with the dirtying of the spark plugs. The present elliptical wear of the cylinder is entirely obviated. The motion is uniform at all times throughout the stroke and is imparted to the driven shaft at its maximum efficiency, thus eliminating vibration and producing an extremely smooth running engine. The cost is somewhat reduced, the construction and fitting of the crank shaft and piston rods is eliminated, the piston slap and pounding of the connecting rods are done away with, so that a substantially noiseless running engine is provided, the compression is increased, and fuel consumption is reduced.

In the form shown on the second sheet of drawings, in Figs. 3 and 4, the same results are secured and the device need not be described in detail, but here the piston rod

itself is provided with a cam groove or track 26 which surrounds it and causes the same motion as above described by its action on a fixed pin or roll 25. The other features above mentioned are the same.

Although I have illustrated and described only two forms of the invention I am aware of the fact that other modifications can be made therein by any person skilled in the art without departing from the scope of the invention as expressed in the claims. Therefore I do not wish to be limited to all the details herein shown and described, but what I do claim is:—

1. In an internal combustion engine, the combination with a set of cylinders and pistons, of a rod connected with each piston, means whereby the longitudinal motion of each rod will cause the rod to turn on its own axis, and means for gearing all said rods together to transmit the motion of rotation from one to another throughout the entire series. 70

2. In an engine, the combination with a set of cylinders and pistons arranged to operate longitudinally, each piston having a rod, a guide outside each cylinder for turning the piston therein as the rod rotates, and means for transmitting the turning motion of each piston to all the others of the engine. 80

3. In an engine, the combination with a set of cylinders and pistons, each piston having a rod, the pistons being arranged to operate alternately, means for turning the pistons as they reciprocate, and a set of gears, one on each rod directly meshing with each other to directly gear the rods together and cause them to rotate always at the same speed. 90

4. In an internal combustion engine, the combination with a set of cylinders and pistons arranged to operate alternately, of a rod connected with each piston, means surrounding and extending along each rod and located at a distance from it for causing the reciprocating motion of the rod to turn the rod and its piston, and means for connecting the rods together to cause them all to turn at the same speed. 100

In testimony whereof I have hereunto affixed my signature. 105

M. L. ZIMMER.
